UNITED STATES PATENT OFFICE

WILLIAM A. H. WELLS, OF EDGEWOOD, RHODE ISLAND

CLASP

Application filed July 29, 1931. Serial No. 553,764.

This invention relates to a clasp of the type used for necklaces and the like, and has for its object to provide a construction which may be economically manufactured and easily operated.

Another object of this invention is the provision of a construction such that the connections to the chain will be prevented from moving into a position to force the clasp to open position.

Another object of the invention is the restriction of the opposite side walls of the clasp to limit the movement of the connections to the chain and assist in preventing them from moving to an appreciable extent from the ends of the clasp.

A further object of the invention is the provision of inwardly bent portions which will engage prior to the movement of the clasp to full open position to prevent bending of the joint end of the tongue to such an extent as to set the stock against returning by its spring action.

A still further object of the invention is to direct the end portion of the hook outwardly to more easily receive the loop of the chain which is to be connected thereto.

With these and other objects and advantageous features in view, the invention consists of a novel arrangement of parts more fully disclosed in the detailed description following, in conjunction with the accompanying drawings, and more particularly set forth in the appended claims.

Fig. 1 is a top plan view of the clasp.

Fig. 2 is a bottom plan view thereof.

Fig. 3 is a side elevation.

Fig. 4 is a plan view of one of the connecting loop links.

Fig. 5 is a side elevation showing the tongue of the clasp moved to open position.

It has been common to use spring rings for connecting together the ends of a necklace chain or the like, which spring rings have certain disadvantages such as presenting little surface for ornamentation and being more expensive to manufacture than the present invention. I have provided a clasp which may be substituted for the spring ring, which is bent from a single piece of flat wire provid-

ing a substantial surface for ornamentation or the like, and which may be inexpensively manufactured and assembled with a pair of loops which are connected to the chain and which may be released from the clasp as desired, and in order that these loops may be retained at the opposite folded ends of the clasp, I have bent the opposite walls of the clasp inwardly at a point spaced from, but adjacent to, the folded ends of the clasp so that the passage to the end is restricted and the loops cannot as readily slide along the clasp toward its middle portion to upset the same or permit fouling or twisting of the necklace when worn. These restrictions at the so-called joint end of the clasp also provide a stop for limiting the amount of compression upon the bent or joint end of the tongue, preserving the life of the clasp at the joint; and the following is a detailed description of the present embodiment of this invention illustrating the preferred means by which these advantageous results may be accomplished.

With reference to the drawings, 10 designates the front or top wall of the clasp and 11 the bottom wall or tongue thereof which is integrally connected to the top wall through the fold 12 forming the so-called joint end and which engages the lip 13 of the hook 14 which is integrally connected with the top or front wall by being folded therefrom.

The clasp is made from a strip of flat wire which is folded up into generally band shape as illustrated in Fig. 3 forming the top and bottom wall and hook portion as just previously described. The tongue 11 has its end portion 15 extending beneath the lip 13 of the hook so that the ends of the band overlap each other. The inherent resiliency of the folded stock tends to force the tongue 11 outwardly against the lip 13 but permits the same to be flexed inwardly to the position illustrated in Fig. 5 to open the hook and permit the lip 13 to be threaded through a loop 16 at one end thereof for attachment or detachment of the chain connected to this loop from the clasp.

The joint ends of the clasp is also connect-

ed to a loop 17 which may be threaded over the tongue 11 when the clasp is in open position and which is connected to the opposite end of the chain which it is intended shall be permanently connected to the clasp. The loops 16 and 17 are of substantially identical construction.

In order that the loops 16 and 17 may be retained in their respective ends of the clasp, I have bent the top wall and the hook portion inwardly as at 18 and 19 toward each other to restrict the eye 20 of the folded hook in which the loop is located. By this arrangement, should the loop 16 be moved or drawn around the hook 14 towards the overlapping of the lip and tongue the inward projection 19 will cause the same to pass the portion of the lip 13 between the projection 19 and its end so that it will engage the tongue to close 20 rather than open the clasp at the overlapping portions of the band. In a similar manner I have restricted the eye 21 in which the loop 17 is located by bending inwardly the stock of the top wall as at 22 and the stock of the 25 bottom wall or tongue as at 23, so as to prevent this loop from moving along the clasp to disarrange the loop with reference to the chain and make an untidy appearance when worn.

30 The inwardly bent portions 22 and 23 serve also as abutment portions when the tongue 11 is moved to open position as illustrated in Fig. 5 whereby the amount of flexing at the joint end 12 is limited. After the inwardly bent portions 22 and 23 are in engagement, further flexing of the tongue occurs between the point 23 and the end 15 thereof.

35 The loops 16 and 17 are shaped with their ends 24 and 25 overlapping on an angle to make a smooth and strong joint. Each loop is flattened along the portion at which this overlapping occurs to provide a smoother hinge action between the loop and the flattened strip of stock from which the clasp is bent (see Figs. 1 and 2). The loop is also provided with restricted portions 26 and 27 to provide a generally circular eye or opening 28 for the reception of a chain link or other means of connecting the loop to a chain. 40 This restriction and flattened portion also prevents the loop from being rotated about an axis within itself with reference to the clasp so that the chain is always in the desired position with reference to the clasp.

45 By this arrangement and construction, I have provided a clasp which by reason of its similar inwardly deflected portions adjacent each end a symmetrical appearance is provided which is pleasing and attractive.

50 The foregoing description is directed solely towards the construction illustrated, but I desire it to be understood that I reserve the privilege of resorting to all the mechanical changes to which the device is susceptible, the

invention being defined and limited only by the terms of the appended claims.

I claim:

1. A clasp comprising a strip of flat wire having a front portion and folded at each end to provide a tongue extending from one end and a hook from the other end beneath the end of which hook said tongue extends, said folded end portions being both restricted at a point spaced inwardly from the extremities of the fold. 70

2. A clasp comprising a strip of flat wire folded to provide a band or loop with its ends overlapping nearer one end than the middle, and the opening between the opposite sides 80 of the band being restricted adjacent each end of the band, the outer end portion extending outwardly at an angle to the general extent of the band from the point of said restricted portion. 85

3. A clasp comprising a strip of flat wire folded to provide a band with its ends overlapping nearer one end than the other, said band being bent inwardly from both sides at a point spaced from the fold to provide an opening with a restricted neck. 90

4. A clasp comprising a strip of flat wire folded to provide a band with its ends overlapping nearer one end than the other, said band being bent inwardly adjacent each end 95 from both sides at a point spaced from the folded ends to provide openings between the opposite sides of the band with restricted neck portions. 100

5. A clasp comprising a strip of flat wire 100 folded to provide a band with its ends overlapping nearer one end than the other, said band being bent inwardly from both sides at a point spaced from the fold to provide an opening with a restricted neck, and a loop in 105 said opening with a flattened side engaging said fold.

6. A clasp comprising a strip of flat wire bent to provide a front portion, a hook and a tongue closing the hook, said front portion 110 and tongue being bent inwardly toward each other adjacent the fold between the front portion and tongue to provide abutment portions to engage upon flexing the tongue a predetermined amount. 115

In testimony whereof I affix my signature.

WILLIAM A. H. WELLS.
